CLAIM

The ornamental design for a cap as shown and described.

DESCRIPTION

FIG. 1 is a top perspective view of a first embodiment of a cap with the text of Florida, showing our new design;

FIG. 2 is a top elevational view thereof;

FIG. 3 is a rear elevational view thereof;

FIG. 4 is a front elevational view thereof;

FIG. 5 is a right side elevational view thereof;

FIG. 6 is a left side elevational view thereof;

FIG. 7 is a bottom elevational view thereof;

FIG. 8 is a top perspective view of a second embodiment of a cap with the text of Miami, showing our new design;

FIG. 9 is a top elevational view thereof;

FIG. 10 is a rear elevational view thereof;

FIG. 11 is a front elevational view thereof;

FIG. 12 is a right side elevational view thereof;

FIG. 13 is a left side elevational view thereof;

FIG. 14 is a bottom elevational view thereof;

FIG. 15 is a top perspective view of a third embodiment of a cap with the text of Orlando, showing our new design;

FIG. 16 is a top elevational view thereof;

FIG. 17 is a rear elevational view thereof;

FIG. 18 is a front elevational view thereof;

FIG. 19 is a right side elevational view thereof;

FIG. 20 is a left side elevational view thereof;

FIG. 21 is a bottom elevational view thereof;

FIG. 22 is a top perspective view of a fourth embodiment of a cap with the text of The Florida Keys, showing our new design;

FIG. 23 is a top elevational view thereof;

FIG. 24 is a rear elevational view thereof;

FIG. 25 is a front elevational view thereof;

FIG. 26 is a right side elevational view thereof;

FIG. 27 is a left side elevational view thereof;

(Continued)

FIG. 28 is a bottom elevational view thereof;
FIG. 29 is a top perspective view of a fifth embodiment of a cap with the text of Key West, showing our new design;
FIG. 30 is a top elevational view thereof;
FIG. 31 is a rear elevational view thereof;
FIG. 32 is a front elevational view thereof;
FIG. 33 is a right side elevational view thereof;
FIG. 34 is a left side elevational view thereof;
FIG. 35 is a bottom elevational view thereof;
FIG. 36 is a top perspective view of a sixth embodiment of a cap with the text of New York, showing our new design;
FIG. 37 is a top elevational view thereof;
FIG. 38 is a rear elevational view thereof;
FIG. 39 is a front elevational view thereof;
FIG. 40 is a right side elevational view thereof;
FIG. 41 is a left side elevational view thereof;
FIG. 42 is a bottom elevational view thereof;
FIG. 43 is a top perspective view of a seventh embodiment of a cap with the text of Los Angeles, showing our new design;
FIG. 44 is a top elevational view thereof;
FIG. 45 is a rear elevational view thereof;
FIG. 46 is a front elevational view thereof;
FIG. 47 is a right side elevational view thereof;
FIG. 48 is a left side elevational view thereof;
FIG. 49 is a bottom elevational view thereof;
FIG. 50 is a top perspective view of an eighth embodiment of a cap with the text of California, showing our new design;
FIG. 51 is a top elevational view thereof;
FIG. 52 is a rear elevational view thereof;
FIG. 53 is a front elevational view thereof;
FIG. 54 is a right side elevational view thereof;
FIG. 55 is a left side elevational view thereof;
FIG. 56 is a bottom elevational view thereof;
FIG. 57 is a top perspective view of a ninth embodiment of a cap with the text of San Diego, showing our new design;
FIG. 58 is a top elevational view thereof;
FIG. 59 is a rear elevational view thereof;
FIG. 60 is a front elevational view thereof;
FIG. 61 is a right side elevational view thereof;
FIG. 62 is a left side elevational view thereof;
FIG. 63 is a bottom elevational view thereof;
FIG. 64 is a top perspective view of a tenth embodiment of a cap with the text of San Francisco, showing our new design;
FIG. 65 is a top elevational view thereof;
FIG. 66 is a rear elevational view thereof;
FIG. 67 is a front elevational view thereof;
FIG. 68 is a right side elevational view thereof;
FIG. 69 is a left side elevational view thereof;
FIG. 70 is a bottom elevational view thereof;
FIG. 71 is a top perspective view of an eleventh embodiment of a cap with the text of Las Vegas, showing our new design;
FIG. 72 is a top elevational view thereof;
FIG. 73 is a rear elevational view thereof;
FIG. 74 is a front elevational view thereof;
FIG. 75 is a right side elevational view thereof;
FIG. 76 is a left side elevational view thereof;
FIG. 77 is a bottom elevational view thereof;
FIG. 78 is a top perspective view of a twelfth embodiment of a cap with the text of Colorado, showing our new design;
FIG. 79 is a top elevational view thereof;
FIG. 80 is a rear elevational view thereof;
FIG. 81 is a front elevational view thereof;
FIG. 82 is a right side elevational view thereof;

FIG. 83 is a left side elevational view thereof;
FIG. 84 is a bottom elevational view thereof;
FIG. 85 is a top perspective view of a thirteenth embodiment of a cap with the text of Montana, showing our new design;
FIG. 86 is a top elevational view thereof;
FIG. 87 is a rear elevational view thereof;
FIG. 88 is a front elevational view thereof;
FIG. 89 is a right side elevational view thereof;
FIG. 90 is a left side elevational view thereof;
FIG. 91 is a bottom elevational view thereof;
FIG. 92 is a top perspective view of a fourteenth embodiment of a cap with the text of Wyoming, showing our new design;
FIG. 93 is a top elevational view thereof;
FIG. 94 is a rear elevational view thereof;
FIG. 95 is a front elevational view thereof;
FIG. 96 is a right side elevational view thereof;
FIG. 97 is a left side elevational view thereof;
FIG. 98 is a bottom elevational view thereof;
FIG. 99 is a top perspective view of a fifteenth embodiment of a cap with the text of North Dakota, showing our new design;
FIG. 100 is a top elevational view thereof;
FIG. 101 is a rear elevational view thereof;
FIG. 102 is a front elevational view thereof;
FIG. 103 is a right side elevational view thereof;
FIG. 104 is a left side elevational view thereof;
FIG. 105 is a bottom elevational view thereof;
FIG. 106 is a top perspective view of a sixteenth embodiment of a cap with the text of South Beach, showing our new design;
FIG. 107 is a top elevational view thereof;
FIG. 108 is a rear elevational view thereof;
FIG. 109 is a front elevational view thereof;
FIG. 110 is a right side elevational view thereof;
FIG. 111 is a left side elevational view thereof;
FIG. 112 is a bottom elevational view thereof;
FIG. 113 is a top perspective view of a seventeenth embodiment of a cap with the text of Utah, showing our new design;
FIG. 114 is a top elevational view thereof;
FIG. 115 is a rear elevational view thereof;
FIG. 116 is a front elevational view thereof;
FIG. 117 is a right side elevational view thereof;
FIG. 118 is a left side elevational view thereof;
FIG. 119 is a bottom elevational view thereof;
FIG. 120 is a top perspective view of an eighteenth embodiment of a cap with the text of New Mexico, showing our new design;
FIG. 121 is a top elevational view thereof;
FIG. 122 is a rear elevational view thereof;
FIG. 123 is a front elevational view thereof;
FIG. 124 is a right side elevational view thereof;
FIG. 125 is a left side elevational view thereof;
FIG. 126 is a bottom elevational view thereof;
FIG. 127 is a top perspective view of a nineteenth embodiment of a cap with the text of Michigan, showing to our new design;
FIG. 128 is a top elevational view thereof;
FIG. 129 is a rear elevational view thereof;
FIG. 130 is a front elevational view thereof;
FIG. 131 is a right side elevational view thereof;
FIG. 132 is a left side elevational view thereof;
FIG. 133 is a bottom elevational view thereof;

FIG. 134 is a top perspective view of a twentieth embodiment of a cap with the text of Detroit, showing to our new design;

FIG. 135 is a top elevational view thereof;

FIG. 136 is a rear elevational view thereof;

FIG. 136 137 is a front elevational view thereof;

FIG. 138 is a right side elevational view thereof;

FIG. 139 is a left side elevational view thereof;

FIG. 140 is a bottom elevational view thereof;

FIG. 141 is a top perspective view of a twenty-first embodiment of a cap with the text of Wisconsin, showing to our new design;

FIG. 142 is a top elevational view thereof;

FIG. 143 is a rear elevational view thereof;

FIG. 144 is a front elevational view thereof;

FIG. 145 is a right side elevational view thereof;

FIG. 146 is a left side elevational view thereof;

FIG. 147 is a bottom elevational view thereof;

FIG. 148 is a top perspective view of a twenty-second embodiment of a cap with the text of Chicago, showing our new design;

FIG. 149 is a top elevational view thereof;

FIG. 150 is a rear elevational view thereof;

FIG. 151 is a front elevational view thereof;

FIG. 152 is a right side elevational view thereof;

FIG. 153 is a left side elevational view thereof;

FIG. 154 is a bottom elevational view thereof;

FIG. 155 is a top perspective view of a twenty-third embodiment of a cap with the text of Minnesota, showing our new design;

FIG. 156 is a top elevational view thereof;

FIG. 157 is a rear elevational view thereof;

FIG. 158 is a front elevational view thereof;

FIG. 159 is a right side elevational view thereof;

FIG. 160 is a left side elevational view thereof;

FIG. 161 is a bottom elevational view thereof;

FIG. 162 is a top perspective view of a twenty-fourth embodiment of a cap with the text of Hawaii, showing our new design;

FIG. 163 is a top elevational view thereof;

FIG. 164 is a rear elevational view thereof;

FIG. 165 is a front elevational view thereof;

FIG. 166 is a right side elevational view thereof;

FIG. 167 is a left side elevational view thereof;

FIG. 168 is a bottom elevational view thereof;

FIG. 169 is a top perspective view of a twenty-fifth embodiment of a cap with the text of Honolulu, showing our new design;

FIG. 170 is a top elevational view thereof;

FIG. 171 is a rear elevational view thereof;

FIG. 172 is a front elevational view thereof;

FIG. 173 is a right side elevational view thereof;

FIG. 174 is a left side elevational view thereof;

FIG. 175 is a bottom elevational view thereof;

FIG. 176 is a top perspective view of a twenty-sixth embodiment of a cap with the text of Boston, showing our new design;

FIG. 177 is a top elevational view thereof;

FIG. 178 is a rear elevational view thereof;

FIG. 179 is a front elevational view thereof;

FIG. 180 is a right side elevational view thereof;

FIG. 181 is a left side elevational view thereof;

FIG. 182 is a bottom elevational view thereof;

FIG. 183 is a top perspective view of a twenty-seventh embodiment of a cap with the text of North Carolina, showing our new design;

FIG. 184 is a top elevational view thereof;

FIG. 185 is a rear elevational view thereof;

FIG. 186 is a front elevational view thereof;

FIG. 187 is a right side elevational view thereof;

FIG. 188 is a left side elevational view thereof;

FIG. 189 is a bottom elevational view thereof;

FIG. 190 is a top perspective view of a twenty-eighth embodiment of a cap with the text of South Carolina, showing our new design;

FIG. 191 is a top elevational view thereof;

FIG. 192 is a rear elevational view thereof;

FIG. 193 is a front elevational view thereof;

FIG. 194 is a right side elevational view thereof;

FIG. 195 is a left side elevational view thereof;

FIG. 196 is a bottom elevational view thereof;

FIG. 197 is a top perspective view of a twenty-ninth embodiment of a cap with the text of Myrtle Beach, showing our new design;

FIG. 198 is a top elevational view thereof;

FIG. 199 is a rear elevational view thereof;

FIG. 200 is a front elevational view thereof;

FIG. 201 is a right side elevational view thereof;

FIG. 202 is a left side elevational view thereof;

FIG. 203 is a bottom elevational view thereof;

FIG. 204 is a top perspective view of a thirtieth embodiment of a cap with the text of Hilton Head, showing our new design;

FIG. 205 is a top elevational view thereof;

FIG. 206 is a rear elevational view thereof;

FIG. 207 is a front elevational view thereof;

FIG. 208 is a right side elevational view thereof;

FIG. 209 is a left side elevational view thereof;

FIG. 210 is a bottom elevational view thereof;

FIG. 211 is a top perspective view of a thirty-first embodiment of a cap with the text of Texas, showing our new design;

FIG. 212 is a top elevational view thereof;

FIG. 213 is a rear elevational view thereof;

FIG. 214 is a front elevational view thereof;

FIG. 215 is a right side elevational view thereof;

FIG. 216 is a left side elevational view thereof;

FIG. 217 is a bottom elevational view thereof;

FIG. 218 is a top perspective view of a thirty-second embodiment of a cap with the text of Washington DC, showing our new design;

FIG. 219 is a top elevational view thereof;

FIG. 220 is a rear elevational view thereof;

FIG. 221 is a front elevational view thereof;

FIG. 222 is a right side elevational view thereof;

FIG. 223 is a left side elevational view thereof;

FIG. 224 is a bottom elevational view thereof;

FIG. 225 is a top perspective view of a thirty-third embodiment of a cap with the text of New Orleans, showing our new design;

FIG. 226 is a top elevational view thereof;

FIG. 227 is a rear elevational view thereof;

FIG. 228 is a front elevational view thereof;

FIG. 229 is a right side elevational view thereof;

FIG. 230 is a left side elevational view thereof;

FIG. 231 is a bottom elevational view thereof;

FIG. 232 is a top perspective view of a thirty-fourth embodiment of a cap with the text of Atlanta, showing our new design;
FIG. 233 is a top elevational view thereof;
FIG. 234 is a rear elevational view thereof;
FIG. 235 is a front elevational view thereof;
FIG. 236 is a right side elevational view thereof;
FIG. 237 is a left side elevational view thereof;
FIG. 238 is a bottom elevational view thereof;
FIG. 239 is a top perspective view of a thirty-fifth embodiment of a cap with the text of Georgia, showing our new design;
FIG. 240 is a top elevational view thereof;
FIG. 241 is a rear elevational view thereof;
FIG. 242 is a front elevational view thereof;
FIG. 243 is a right side elevational view thereof;
FIG. 244 is a left side elevational view thereof;
FIG. 245 is a bottom elevational view thereof;
FIG. 246 is a top perspective view of a thirty-sixth embodiment of a cap with the text of Savannah, showing our new design;
FIG. 247 is a top elevational view thereof;
FIG. 248 is a rear elevational view thereof;
FIG. 249 is a front elevational view thereof;
FIG. 250 is a right side elevational view thereof;
FIG. 251 is a left side elevational view thereof;
FIG. 252 is a bottom elevational view thereof;
FIG. 253 is a top perspective view of a thirty-seventh embodiment of a cap with the text of Destin, showing our new design;
FIG. 254 is a top elevational view thereof;
FIG. 255 is a rear elevational view thereof;
FIG. 256 is a front elevational view thereof;
FIG. 257 is a right side elevational view thereof;
FIG. 258 is a left side elevational view thereof;
FIG. 259 is a bottom elevational view thereof;
FIG. 260 is a top perspective view of a thirty-eighth embodiment of a cap with the text of Panama City Beach, showing our new design;
FIG. 261 is a top elevational view thereof;
FIG. 262 is a rear elevational view thereof;
FIG. 263 is a front elevational view thereof;
FIG. 264 is a right side elevational view thereof;
FIG. 265 is a left side elevational view thereof;
FIG. 266 is a bottom elevational view thereof;
FIG. 267 is a top perspective view of a thirty-ninth embodiment of a cap with the text of Clearwater, showing our new design;
FIG. 268 is a top elevational view thereof;
FIG. 269 is a rear elevational view thereof;
FIG. 270 is a front elevational view thereof;
FIG. 271 is a right side elevational view thereof;
FIG. 272 is a left side elevational view thereof;
FIG. 273 is a bottom elevational view thereof;
FIG. 274 is a top perspective view of a fortieth embodiment of a cap with the text of Tampa, showing our new design;
FIG. 275 is a top elevational view thereof;
FIG. 276 is a rear elevational view thereof;
FIG. 277 is a front elevational view thereof;
FIG. 278 is a right side elevational view thereof;
FIG. 279 is a left side elevational view thereof;
FIG. 280 is a bottom elevational view thereof;
FIG. 281 is a top perspective view of a forty-first embodiment of a cap with the text of Daytona, showing our new design;

FIG. 282 is a top elevational view thereof;
FIG. 283 is a rear elevational view thereof;
FIG. 284 is a front elevational view thereof;
FIG. 285 is a right side elevational view thereof;
FIG. 286 is a left side elevational view thereof;
FIG. 287 is a bottom elevational view thereof;
FIG. 288 is a top perspective view of a forty-second embodiment of a cap with the text of Pensacola Beach, showing our new design;
FIG. 289 is a top elevational view thereof;
FIG. 290 is a rear elevational view thereof;
FIG. 291 is a front elevational view thereof;
FIG. 292 is a right side elevational view thereof;
FIG. 293 is a left side elevational view thereof;
FIG. 294 is a bottom elevational view thereof;
FIG. 295 is a top perspective view of a forty-third embodiment of a cap with the text of Tennessee, showing our new design;
FIG. 296 is a top elevational view thereof;
FIG. 297 is a rear elevational view thereof;
FIG. 298 is a front elevational view thereof;
FIG. 299 is a right side elevational view thereof;
FIG. 300 is a left side elevational view thereof;
FIG. 301 is a bottom elevational view thereof;
FIG. 302 is a top perspective view of a forty-fourth embodiment of a cap with the text of Saipan, showing our new design;
FIG. 303 is a top elevational view thereof;
FIG. 304 is a rear elevational view thereof;
FIG. 305 is a front elevational view thereof;
FIG. 306 is a right side elevational view thereof;
FIG. 307 is a left side elevational view thereof;
FIG. 308 is a bottom elevational view thereof;
FIG. 309 is a top perspective view of a forty-fifth embodiment of a cap with the text of Maui, showing our new design;
FIG. 310 is a top elevational view thereof;
FIG. 311 is a rear elevational view thereof;
FIG. 312 is a front elevational view thereof;
FIG. 313 is a right side elevational view thereof;
FIG. 314 is a left side elevational view thereof;
FIG. 315 is a bottom elevational view thereof;
FIG. 316 is a top perspective view of a forty-sixth embodiment of a cap with the text of Guam, showing our new design;
FIG. 317 is a top elevational view thereof;
FIG. 318 is a rear elevational view thereof;
FIG. 319 is a front elevational view thereof;
FIG. 320 is a right side elevational view thereof;
FIG. 321 is a left side elevational view thereof;
FIG. 322 is a bottom elevational view thereof;
FIG. 323 is a top perspective view of a forty-seventh embodiment of a cap with the text of Puerto Rico, showing our new design;
FIG. 324 is a top elevational view thereof;
FIG. 325 is a rear elevational view thereof;
FIG. 326 is a front elevational view thereof;
FIG. 327 is a right side elevational view thereof;
FIG. 328 is a left side elevational view thereof;
FIG. 329 is a bottom elevational view thereof;
FIG. 330 is a top perspective view of a forty-eighth embodiment of a cap with the text of Arizona, showing our new design;
FIG. 331 is a top elevational view thereof;

FIG. 332 is a rear elevational view thereof;
 FIG. 333 is a front elevational view thereof;
 FIG. 334 is a right side elevational view thereof;
 FIG. 335 is a left side elevational view thereof;
 FIG. 336 is a bottom elevational view thereof;
 FIG. 337 is a top perspective view of a forty-ninth embodiment of a cap with the text of Charleston, showing our new design;
 FIG. 338 is a top elevational view thereof;
 FIG. 339 is a rear elevational view thereof;
 FIG. 340 is a front elevational view thereof;
 FIG. 341 is a right side elevational view thereof;
 FIG. 342 is a left side elevational view thereof;
 FIG. 343 is a bottom elevational view thereof;
 FIG. 344 is a top perspective view of a fiftieth embodiment of a cap with the text of Dallas, showing our new design;
 FIG. 345 is a top elevational view thereof;
 FIG. 346 is a rear elevational view thereof;
 FIG. 347 is a front elevational view thereof;
 FIG. 348 is a right side elevational view thereof;
 FIG. 349 is a left side elevational view thereof;
 FIG. 350 is a bottom elevational view thereof;
 FIG. 351 is a top perspective view of a fifty-first embodiment of a cap with the text of Denver, showing our new design;
 FIG. 352 is a top elevational view thereof;
 FIG. 353 is a rear elevational view thereof;
 FIG. 354 is a front elevational view thereof;
 FIG. 355 is a right side elevational view thereof;
 FIG. 356 is a left side elevational view thereof;
 FIG. 357 is a bottom elevational view thereof;
 FIG. 358 is a top perspective view of a fifty-second embodiment of a cap with the text of Houston, showing our new design;
 FIG. 359 is a top elevational view thereof;
 FIG. 360 is a rear elevational view thereof;
 FIG. 361 is a front elevational view thereof;
 FIG. 362 is a right side elevational view thereof;
 FIG. 363 is a left side elevational view thereof;
 FIG. 364 is a bottom elevational view thereof;
 FIG. 365 is a top perspective view of a fifty-third embodiment of a cap with the text of San Antonio, showing our new design;
 FIG. 366 is a top elevational view thereof;
 FIG. 367 is a rear elevational view thereof;
 FIG. 368 is a front elevational view thereof;
 FIG. 369 is a right side elevational view thereof;
 FIG. 370 is a left side elevational view thereof;
 FIG. 371 is a bottom elevational view thereof;
 FIG. 372 is a top perspective view of a fifty-fourth embodiment of a cap with the text of Seattle, showing our new design;
 FIG. 373 is a top elevational view thereof;
 FIG. 374 is a rear elevational view thereof;
 FIG. 375 is a front elevational view thereof;
 FIG. 376 is a right side elevational view thereof;
 FIG. 377 is a left side elevational view thereof; and,
 FIG. 378 is a bottom elevational view thereof.
